(No Model.)

J. HAMLIN.
VETERINARY TOOTH CUTTER.

No. 475,940.

Patented May 31, 1892.

UNITED STATES PATENT OFFICE.

JOHN HAMLIN, OF WASHINGTON, DISTRICT OF COLUMBIA.

VETERINARY TOOTH-CUTTER.

SPECIFICATION forming part of Letters Patent No. 475,940, dated May 31, 1892.

Application filed January 5, 1892. Serial No. 417,092. (No model.)

To all whom it may concern:

Be it known that I, JOHN HAMLIN, a citizen of the United States, residing at Washington, in the District of Columbia, have invented certain new and useful Improvements in Implements for Cutting Off the Teeth of Horses; and I do hereby declare the following to be a full, clear, and exact description of the invention, such as will enable others skilled in the art to which it appertains to make and use the same.

My invention relates to a new and useful improved implement for cutting off the teeth of horses; and it consists of a pair of crossed and pivoted levers and a pair of crossed cutting-jaws loosely connected together by two plates, the rear end of each jaw being pivoted, respectively, to the forward end of each lever in the form of a compound lever, as will be hereinafter more fully described in the specification and particularly set forth in the claim.

It is well known to veterinary surgeons and to others skilled in the art of cutting the teeth of horses that great care must be exercised in cutting off an uneven tooth to avoid crushing or otherwise permanently injuring the teeth and that it is next to impossible to perform the operation successfully with the instruments now in use.

The principal object of the present invention is to provide an implement whose cutting-jaws, when opened and encircling a tooth, will move together—one in advance of the other—with a "shearing" cut, so that all danger of either crushing or splitting the tooth is absolutely avoided. This object is obtained by the construction and arrangement of the various parts, as illustrated in the accompanying drawings, in which—

Figure 1 represents a front plan view of my improved implement with a portion of the handles broken away; Fig. 2, a back plan view of the same, and Fig. 3 an edge view thereof.

Similar letters of reference indicate similar parts throughout the several views.

A A' indicate a pair of operating-levers, having curved ends *a*, which are crossed and

pivoted together by a pivot *a*². Said levers are 50 provided with suitable handles. (Not shown in the drawings.)

B B' indicate two lever cutting-jaws, which are crossed and connected together by two plates C C'. The lever end of the cutting-jaw B is loosely joined to the curved end of a lever A by a pivot *a*³, and the lever end of the jaw B' is loosely joined to the curved end *a*⁴ of the lever A' by a pivot *a*⁴. The two pairs of levers thus pivotally connected together 55 form a compound lever, by means of which a steady and powerful leverage is attained.

The cutting-jaws are pivoted between the connecting-plates C and C' by pivots *c* *c*', and each of said jaws is formed with a curved 65 shoulder *b*, which, in conjunction with the curved edge *c*² of the plate C', permits of a slight oscillatory movement to the lever cutting-jaws when the levers A A' are manipulated to cut off a tooth.

It will be noticed that the cutting-edges do not come together when in closed position, but that the points are in closer proximity to each other than the base or heel—that is to say, each edge inclines inwardly. The object of this peculiar formation of the cutting-edges is to insure a complete cut through the enamel of the tooth and as far around the latter as is possible.

In using the cutter the jaws are caused to 80 open by spreading apart the levers A A', and the tooth to be cut being encircled by the jaws the said levers are closed. In the act of closing the levers one of the jaws, by reason of the peculiar pivotal connection of 85 the plates and jaws and the operating of the curved edge *c*² on the curved shoulders *b* *b*, will move slightly in advance of the other, as seen by the dotted line in Fig. 2, thus giving a slight shearing cut.

The tooth is easily, quickly, and smoothly cut, and all tendency to crush or split the tooth is avoided.

Having thus described my invention, what I claim is—

An implement for cutting the teeth of horses, comprising a pair of crossed and pivoted operating-levers, a pair of cutting-jaw

levers pivotally connected with the forward ends of the operating levers, and the connecting-plates between which the cutting-jaw levers are independently and loosely pivoted, 5 whereby one cutting-jaw will move slightly in advance of the other, substantially as specified.

In testimony whereof I affix my signature in the presence of two witnesses.

JOHN HAMLIN.

Witnesses:

JAMES G. JESTER,
LEWIS I. O'NEAL.
